UNITED STATES PATENT OFFICE

GUSTAVE W. BERTHOLD, OF CHICAGO, ILLINOIS

PANEL BOARD

Application filed June 1, 1925. Serial No. 33,928.

The present invention relates to improvements in panel boards for distributing electric power to a plurality of load circuits.

The primary object of the invention is to provide a novel panel board for a three-wire system which is small and compact in construction, but in which the bus-bars and other conducting parts are sufficiently spaced apart in air and in insulation to prevent short circuiting.

Another object is to provide a panel board for a three-wire system which can utilize standard double pole switches mounted directly over the bus-bars at the middle of the board.

A further object is to provide a panel board in which the switches are arranged in sections corresponding to sections of the fuse socket members, and permitting the switches to be substituted and rearranged to adapt them to the varying requirements of the load circuits leading from the board.

Stated more specifically, it is an object of the invention to produce a novel panel board for a three-wire system which is of less dimensions both as to length and width than three-wire panel boards heretofore known; and to construct and arrange the parts or elements on the board so that they occupy no greater space than a two-wire panel board, so that the bus-bars and cross bars branching therefrom are spaced to accommodate switches of standard size, dimensions and spacings of mounting-centers. With this object in view I arrange the fuse sockets in a plane spaced away from the bus-bars a considerably greater distance than is usual, and I locate branch or cross bars leading from the neutral bus-bar in a plane between the planes of said fuse sockets and bus-bars. This permits of locating the fuse sockets along each side of the board close together which effects a very substantial shortening of the longitudinal dimension of the panel board as a whole. I also arrange branch or cross bars leading from the outer or positive main bus-bars inwardly to overlie the neutral bus-bar in a plane spaced therefrom, and these inwardly leading branch bars last mentioned also constitute supports or mounting brackets spaced apart a distance

equal to the mounting centers of standard double pole switches, so that these switches may be mounted directly overlying the main bus-bars in the space between the two rows of fuse receptacles along opposite sides of said main bus-bars. The result of this arrangement of the parts or elements on the board is a very substantial saving in the space, both length and width, occupied by the board, which enables me to construct a three-wire system board occupying no greater space than a two-wire board of the type now known.

Ancillary objects and advantages will become apparent as the description proceeds.

In the accompanying drawings, Fig. 1 is a fragmentary front elevation of a panel board embodying the features of my invention.

Fig. 2 is a sectional view thereof taken in the plane of line 2-2 of Fig. 1.

Fig. 3 is an outside view of one of the blocks constituting the fuse socket members.

Fig. 4 is a rear side view of a section of switches, said view being taken substantially along line 4-4 of Fig. 2.

Fig. 5 is a fragmentary front elevation of the panel board reorganized for use in a two-wire system in which both conductors of each load circuit are fused.

Fig. 6 is a sectional view taken along line 6-6 of Fig. 5.

While the invention is susceptible of various modifications and alternative constructions and adaptations, I have shown in the drawings and will herein describe in detail the preferred embodiment, but it is to be understood that I do not thereby intend to limit the invention to the particular form or adaptation disclosed, but aim to cover all modifications and alternative constructions in different adaptations thereof falling within the spirit and scope of the invention as expressed in the appended claims.

Referring to the exemplary embodiment of the invention, the panel board comprises a base plate 10 of any suitable construction on which two parallel rows of blocks or socket members 11 constructed of insulating

55

70

85

95

100

material are mounted. The blocks are secured to the base plate 10 by screws 12, and are arranged in abutting relation to define a central space or gutter serving to ⁵ close the elements on the panel board. A spacer board 13 of insulating material is secured to the plate 10 by screws 14 between the two rows of blocks 11, and forms the bottom or rear side of the gutter. ¹⁰ Mounted on the board 13 in parallel spaced relation are a positive bus-bar 15, a negative bus-bar 16, and a neutral bus-bar 17 positioned therebetween. These bus-bars are secured in place by screws 18 extending ¹⁵ up through the board 13. Each block or socket member 11 in the present instance is provided with two spaced fuse sockets adapted to receive plug fuses of standard construction. Each of these sockets ²⁰ comprises a metallic shell 19 which fits into a bore 20 in the top of the block 11 and which constitutes the outer contact. A conducting plate 21 fits against the bottom of the shell 19 and extends therefrom outwardly through a lateral opening 22 in the block 11. The outer end of the plate 21 is provided with a binding screw 23.

Resting upon the plate 21 in the shell ²⁵ 19 is an insulating washer 24 on which a conducting washer 25 is positioned. A contact screw 26 supported by the washer 25 extends vertically and loosely through the washer 24, the plate 21, the shell 19, and a bore 27 in the block 11 into a lateral slot ³⁰ 28 opening from said block into the gutter. The washer 25 and the screw 26 constitute the central contact of the fuse socket. The lower end of the screw is threaded into a ³⁵ terminal bar or conducting plate 29 which extends from the gutter into the slot 28, and which acts with said screw to hold the different parts of the socket in rigid assembly. The construction of the socket herein described is old and well known, and forms ⁴⁰ no part of the present invention.

A plurality of conducting cross bars one for each pair of opposed socket members 11, are secured to the neutral bus-bar 17 by screws 31, and extend through horizontal ⁴⁵ openings 32 in the blocks 11 to opposite sides of the panel board. Suitable binding screws 33 are provided on the outer ends of the bars.

⁵⁰ The plates 21 and the cross bars 30 for the respective blocks 11 are connected to the load circuits 34^a, 34^b, 34^c and 34^d, the positive and negative leads of these circuits being connected to the screws 23 and the neutral or common return leads being connected to the screw 33. It is immaterial in the present instance whether the neutral lead is single as in circuits 34^a and 34^d or whether it is branched as in 34^b and 34^c. By branching ⁵⁵ 60 the neutral lead, two independent two wire

load circuits are obtained in which the positive and negative leads only are fused.

To provide the regulation insulating space required in practice between the bus-bars 15 and 16 and the branch bars 30 the latter are ⁷⁰ bent from the neutral bus-bar 17 so as to extend across the former at a substantial distance therefrom in a plane between the plane of the bus-bars and the plane of the fuse sockets. It will be evident that the insulation between the cross bars 30 and the fuse sockets in air and in the blocks 11 will depend upon the distance between the sockets of each row. To permit the sockets to be positioned closely together the insulating ⁷⁵ blocks 11 are formed of such a height that the cross bars 30 may be amply spaced from both the bus bars and the sockets. In the present instance the space between the sockets is substantially equal to the width of one of the cross bars 30, but the component distance of the horizontal and vertical distances between each cross bar 30 and the adjacent conducting parts, such as the shells 19 and the conducting plates 21 and 29, is still great ⁸⁰ enough to provide adequate insulation. By virtue of this construction, a short three wire system panel board is obtained.

Conducting cross bars 35, one for each pair of opposed fuse sockets, are mounted alternately on the bus-bars 15 and 16, to which they are secured by screws 36, and are bent to extend forwardly and inwardly therefrom over the neutral bus-bar 17. The inner ends of these cross bars are in substantially the ⁹⁰ same horizontal plane as the conducting plates 29 and in each instance in alinement with the plates adjacent thereto.

Mounted on the conducting plates 29 and the cross bars 35 are two rows of electrical ⁹⁵ switches of standard construction. These switches can be either single pole switches 37 or double pole switches 38, the former each serving to connect one plate with the opposed bar 35, and the latter each serving to connect the two plates 29 of one socket element 11 with the opposed bars 35. The switches are secured in place with screws 39 which are threaded into the plates 29 and the cross bars 35. The double pole switches ¹⁰⁰ 38 are each formed with four slots 40 constituting mounting centers which fit under the heads of the screws 39, and which are spaced apart standard distances adapting said switches primarily to panel boards for two ¹⁰⁵ wire systems. By increasing the depth of the blocks 11 as has been described to permit the sockets to be positioned closely together, the cross bars 35 and plates 29 are spaced longitudinally of the board to accommodate ¹¹⁰ the mounting centers of these standard double pole switches, thereby permitting said switches to be mounted over the main bus-bars in the space between the two rows of ¹¹⁵ sockets. The result of this arrangement is ¹²⁰ ¹²⁵ ¹³⁰

that a narrow board is obtained. By shortening and narrowing the board in the manner described, I can provide a compact board for a three wire system occupying no greater space than boards for two wire systems now known.

It will be noted that the panel board is made up of a plurality of units or sections each of which comprises a pair of insulating blocks at opposite sides of the bus-bars, two fuse sockets in each block, one cross bar 30 extending from the neutral bus-bar and through the blocks in a plane between the plane of the bus-bars and the plane of the sockets, two cross bars 35 extending respectively from the positive and negative bus-bars over the neutral bus-bar, and switches connecting the last mentioned cross bars with the sockets. This permits the panel board to be built up to accommodate different numbers of load circuits.

Each switch comprises a pair of opposed spring clips 41, a double contact blade 42 adapted to engage and bridge said clips, and an operating lever 43 for actuating said blade. Since the construction of the switch is old and well known, it is shown more or less diagrammatically.

The switches 37 and 38 are also secured to the inner sides of a series of plates 44 which engage notches 45 in the adjacent upper edges of the blocks 11, and which serve to close the gutter of the panel board. In the present instance one plate 44 is provided for each pair of opposed blocks 11 constituting a unit, and the adjacent edges 46 of the plates are bent to overlap, thereby arranging the switches into units or sections which can be removed and substituted at will without opening the entire gutter. The switches can be easily and conveniently rearranged. Thus a double pole switch 38 may be substituted for two single pole switches 37, and vice versa.

Figs. 5 and 6 illustrate the changes in the above panel board necessary to adapt it to a two wire system wherein both leads of each load circuit are fused. The cross bars 30 are unnecessary in this arrangement, and can be removed, if desired. The conducting plates 21 are connected to load circuits 47^a, 47^b, 47^c and 47^d, of which each negative lead is connected through one of the fuse sockets the associated conducting plate 29, and a U-shaped bracket 48 to the bus-bar 17, and each positive lead is connected through another fuse socket, associated conducting plate 29, and one cross bar 35 to one of the bus-bars 15 or 16. Each bracket 48 is mounted directly on the bus-bar 17, and serves the two adjacent fuse sockets. One half of the cross bars 35 are displaced by the brackets 48, and the remaining one half are arranged alternately. It will be evident that the panel board while intended primarily for a three

wire system can thus be used for a two wire system in which only the positive leads are fused or in which both the positive and negative leads are fused. This universal adaptability is highly advantageous in the manufacture and use of the panel board.

I claim as my invention:

1. A panel board comprising, in combination, three parallel bus-bars which are, respectively, positive, negative and neutral, two rows of fuse sockets mounted on insulating blocks extending along opposite sides of the set of bus-bars and forming a gutter, said bus-bars being located in a plane at the rear side or bottom of the gutter and said sockets being located in a plane adjacent to the front or open side of the gutter, cross bars leading from said neutral bus-bar in opposite directions and extending through openings in said opposed blocks in a plane between the respective planes of said bus-bars and sockets, means closing the front or open side of said gutter, two rows of switches located beneath said closing means and having their operating posts extending through said closing means, and means for connecting said switches to said positive and negative bus-bars and said sockets comprising terminal bars connected to said sockets and projecting inwardly into said gutter and other terminal bars attached to said positive and negative bus-bars and extending forwardly to the plane of the first mentioned terminal bars, both sets of terminal bars being attached to said switches.

2. A panel board comprising, in combination, three parallel bus-bars of which the middle bar is neutral and the outer bars are positive and negative respectively, two rows of fuse sockets mounted on insulating blocks extending along opposite sides of the set of bus-bars forming a gutter, said bus-bars being located in a plane at the rear side or bottom of the gutter and said sockets being located in a plane adjacent to the front or open side of the gutter, cross bars leading from said neutral bus-bar in opposite directions and extending in front of either said positive or said negative bars and through openings in said opposed blocks in a plane between the respective planes of said bus-bars and sockets, plate means closing the front or open side of said gutter, two rows of switches located beneath said plate means and having their operating posts projecting therethrough, and means for connecting said switches to said positive and negative bus-bars and said sockets comprising conducting plates connected to said sockets and projecting inwardly into said gutter and cross bars attached to said positive and negative bus-bars and extending forwardly to the plane of said conducting plates and thence into a position overlying the neutral bus-bar, said

conducting plates and said last mentioned cross bars being attached to said switches.

3. A panel board unit comprising, in combination, three bus-bars, two insulating blocks mounted at opposite sides of the set of bus-bars, two fuse plug sockets mounted in each of said blocks, the two sockets in each block being in a line parallel with said bus-bars, a cross bar leading from one of said bus-bars in opposite directions through openings in said two blocks, a plate closing the space between said blocks and overlying said bus-bars, two pairs of opposed switches mounted on the inner side of said plate, two bars leading from said pairs of switches respectively to the remaining two of said bus-bars respectively, and four bars, two leading respectively from the switches of each pair to one of the two sockets in each of said opposed blocks respectively. 70

4. A panel board unit comprising, in combination, three bus-bars of which the middle one is neutral and the outer ones positive and negative respectively, two insulating blocks located at opposite sides of the set of bus-bars and forming between them a gutter at the rear side or bottom of which said bus-bars are located, two fuse plug sockets in the front face of each of said blocks in a plane spaced from the plane of said bus-bars, a cross bar leading from said neutral bus-bar outwardly in opposite directions and extending over said positive and negative bus-bars and through openings in said blocks in a plane between the respective planes of said bus-bars and sockets, switches located in said gutter overlying said bus-bars, and means for connecting said switches to said positive and negative bus-bars and said sockets respectively. 85

5. A panel board having, in combination, three parallel bus-bars which are respectively positive, negative and neutral, two rows of insulating blocks mounted on opposite sides of the set of bus-bars, each insulating block having two fuse sockets and each pair of opposed blocks constituting a unit, cross bars leading from the neutral bus-bar through openings in said blocks and mainly located in a plane between the plane of said bus-bars and the plane of said sockets, switches overlying the bus-bars, means for connecting said switches respectively to the positive and negative bus-bars and the sockets, and a plurality of plates, one for each unit of blocks, closing the space between said blocks and overlying said bus-bars. 90

6. A panel board unit comprising, in combination, three bus-bars, two insulating blocks mounted at opposite sides of the set of bus-bars, two fuse plug sockets mounted in each of said blocks and having terminal plates extending into the space between said blocks, a cross bar leading from one of said

bus-bars in opposite directions through openings in said two blocks, two cross bars extending respectively from the other two bus-bars over said first bar, and a plurality of switches adapted to connect said last mentioned cross bars with said terminal plates. 105

7. A panel board having, in combination, a plurality of bus-bars, two rows of fuse sockets mounted at opposite sides of said set of bus-bars, said fuse sockets having conducting plates extending into the space between said sockets and at a substantial distance out from said bars, a plurality of cross bars secured to said bus-bars and extending outwardly therefrom into the plane of said conducting plates, and a plurality of switches mounted on said plates and said cross bars between said rows of sockets and over said bus-bars. 115

8. A panel board having, in combination, a plurality of bus-bars, two rows of fuse sockets mounted at opposite sides of said set of bus-bars, said fuse sockets having conducting plates extending into the space between said sockets and at a substantial distance out from said bus-bars, a bracket mounted on one of said bus-bars of one polarity and extending outwardly therefrom into the plane of said conducting plates, a cross bar secured to another of said bus-bars of another polarity and extending outwardly therefrom into the plane of said conducting plates and over said first bus-bar, and switch means mounted on and connecting said bracket and said cross bar respectively with said conducting plates. 120

In testimony whereof, I have hereunto affixed my signature. 130
